UNITED STATES PATENT OFFICE.

WINFIELD E. HINSDALE, OF TRENTON, NEW JERSEY.

LAVATORY.

1,300,268.

Specification of Letters Patent.

Patented Apr. 15, 1919.

Application filed November 9, 1917. Serial No. 201,152.

To all whom it may concern:

Be it known that I, WINFIELD E. HINSDALE, a citizen of the United States, residing at Trenton, in the county of Mercer and State of New Jersey, have invented a certain new and useful Improvement in Lavatories, of which the following is a specification.

This invention relates to lavatories made of clay, and in trade known as china, vitreous china, etc., and has for its object the improving of the construction of the lavatory in its supply and overflow detail, as to appearance, as to a more certain result in manufacture, a more sanitary device in use, and one that shall be more nearly free of danger from damage in use by reason of unequal expansion than those now on the market.

Lavatories constructed in accordance with my invention are of the one-piece type; that is, the basin, slab, overflow, mixing chamber, nozzle inlet to the basin and supply in the finished product are integral, and the approved forms of hooded nozzle inlet and semiconcealed overflow are incorporated in the complete design.

The essence of my invention resides in my improved form of mixing chamber, the form and position of supply inlets and the means provided for cleansing the overflow independent of the action of the user.

The improved lavatory basin forming the basis of the present invention is illustrated in the annexed drawings, wherein:

Fig. 1 is a vertical sectional view from front to back taken through the mixing chamber and its outlet to the basin and also through the overflow;

Fig. 2 a similar view of the rear portion of the basin on the line II-II of Fig. 4, the faucet and pipe connections being omitted;

Fig. 3 a horizontal sectional view on the line III-III of Fig. 2, and illustrating more particularly the hot and cold water inlets, upper portion of the overflow, and the jet orifices leading thereto;

Fig. 4 a top plan view illustrative of the position of the overflow, mixing chamber and outlet from said chamber to the basin;

Fig. 5 a vertical sectional view, taken on the line V-V of Fig. 4, showing the mixing or supply chamber, its inlets and discharge

to the basin, and the overflow and its jet orifices extending from the mixing and supply chamber; and

Fig. 6 a rear elevation, showing one of the supply controlling valves in place.

Like parts in all the views are designated by similar numerals.

The body or basin proper is designated by 1, and is provided with the usual outlet 2. 3 designates the overflow opening extending into an overflow passage or channel 4, the lower laterally-extending end of which terminates in the outlet 2.

Extending up alongside of the upper part of the channel 4 and over the top thereof is the water inlet and mixing chamber 5, which terminates in the forwardly-extending discharge orifice 6. The walls of said chamber 70 are integral with those of the overflow and likewise integral with the superimposed covering slab or top 7.

Jet openings 8 extend from the mixing or inlet chamber 5 into the overflow channel 75 near the upper end thereof, said openings preferably standing in line with tapered openings 9 formed in the outer walls of the supply or mixing chamber. Water passing through such openings washes down the 80 walls of the overflow channel, and this without any attention on the part of the user of the lavatory. Expansible couplings 10 are fitted in the openings 9, and a valve 11 is connected to each coupling by a pipe-section 85 12. The valve bodies lie below and in line with openings 13 formed in the slab 7, and by prolonging the upwardly-extending threaded portion of the valve I am enabled by the lock nuts 14 and 15 to properly secure 90 the valve in place, and this without any strain being exerted upon the parts. A china cap or escutcheon 16 may be placed over the upper part of the valve, said cap being held in position by a tubular nut 17, 95 screwed down on the top thereof. This arrangement does away with the necessity of making a water-tight joint at the slab, and also takes care of any inequalities in the slab structure, as well as permitting the ready assembly of the parts without undue expenditure of labor.

The slab 7 will also preferably be provided with an opening 18, through which

the usual waste fixtures extend. Such fixtures are omitted from the showing in the drawings.

I am aware that heretofore passages of 5 various kinds have been used in china laboratories for the purpose of creating an integral inlet, but so far as I am advised they have all depended on the thickening of that part of the lavatory to which they were attached, either by superimposing a shaped body of china on top of the lavatory or, in reverse, molding extra china below the slab, producing extra thick walls of china at the point where the passages are placed. Such 10 construction causes unequal drying in the process of manufacture and consequently cracks in the ware and a high loss of laboratories in the fire. Water passages have been made with their ends coincident with the 15 supply-holes through the slab and with a secondary passage intermediate the ends leading to the basin. This method of manufacture necessitated great care in putting the parts together to prevent unequal drying 20 between the first part of the slab molded and the applied walls forming the passages, and brought about a loss either before or 25 after the lavatory had been fired.

It is, of course, to be understood that 30 while the completed fixture, as to the chinaware, was an integral unit, the fixture was made up from a plurality of pieces that were processed together, and uniformity of thickness of walls and similar temper of pieces 35 were necessary to insure success in drying and later in vitrifying. Moreover, though the completed lavatory made in the manner just specified may have come from the fire in perfect condition, it was subjected to unusual strain in use because of the fact that, 40 first, the heavy walls of china surrounding the passages and, second, the length of the passages, presented large parts of china to undue expansion and contraction when in use by reason of the sudden heating of the ware on the hot-water side, while on the cold-water side the parts were subjected to contraction during the greater part of the year, which resulted in cracking the 45 lavatory through the walls of the back of the basin and the water inlet. While this cracking did not always destroy the fixture to such an extent that it was useless, it nevertheless detracted from its value as a fixture 50 and marred its beauty of appearance.

With my improved mixing chamber it will be noted upon reference to the drawings that the chamber formed around and over the top of the overflow is defined or formed 60 by walls which are of substantially uniform thickness, and that the distance from one opening 9 to the opposite opening 9 is of the minimum, and only sufficient to clear the overflow walls. It is also to be noted, 65 particularly upon reference to Fig. 1, that

the opening or outlet to the basin from the mixing chamber is quite short. Under this construction, therefore, all the faults of unequal drying, and consequent loss in manufacture, are as nearly eliminated as would 70 seem possible, while the small portion of the lavatory subjected to hot-water strain, with the comparatively thin walls which are of uniform thickness, opposed to the direct action of hot water, reduces the chance of injury in use to the vanishing-point. 75

Moreover, in producing the mixing chamber in the novel manner as above set forth I have also made it possible to attach fittings for supply to the lavatory through the slab 80 or top, and to the openings 9, 9 in straight lines and with a minimum of parts, presenting to the eye no portion of the under fittings, as is common in the usual form of lavatory, and thus reducing the cost of installation, while still retaining adjustability, 85 in that the couplings on the pipe sections 12 allow for a right and left hand adjustment of the valves within any range which the variation in china may demand, and the 90 approved form of valve or faucet used will provide for vertical adjustment to any extent required in that direction.

As above noted, no water-joint is needed at the connection of the faucet to the slab, 95 making it necessary only to tighten the faucet to the slab to such an extent as to insure permanency of position.

While no water entering into the overflow can in any way again come in contact 100 with the user of the basin, still the overflow passage presents an uncleanable surface in nearly all lavatories, and while some lavatories are made with extra large openings for the admission of cleaning cloths, brushes 105 and the like, the majority provide no means (other than such openings) for cleaning the interior walls of such overflow passages; consequently, the passages become foul and more or less of an annoyance. This is overcome in the present construction by providing the jet orifices or openings 8, which extend from the mixing chamber and act whenever one or both of the faucets is turned on to introduce a jet of water into the overflow passage, thus providing for the cleaning 115 of the overflow by keeping the walls washed down at all times and preventing accumulation of deposit. The act of washing the overflow is, of course, in part a function of the supply water and not under direct control of the user and not dependent 120 in any sense upon the user.

I am aware that the prior art discloses water passages through chinaware of laboratories, but believe it broadly new with me to produce a mixing chamber integral with the overflow walls and surrounding the same, and at the same time integral with the superimposed slab of the lavatory, and 130

in which all the walls are of a substantially uniform thickness.

I also believe it to be new with me to provide a chamber which may be fed at its sides in direct line with the supply valve, and the claims are to be construed generically except where they are drawn to a specific construction.

It is evident that by minor modifications of the construction herein set forth the mixing chamber may be supplied from the rear if conditions obtain that make this connection advisable. Such construction is not shown for the reason that it is clearly evident how it could be carried out from the showing above made.

Having thus described my invention, what I claim is:

1. In a one-piece lavatory, the combination of a basin; a slab; an overflow; independent inlets for hot and cold water arranged on opposite sides of the upper portion of the overflow; and a mixing chamber above the overflow into which the inlets discharge, said chamber in turn discharging into the basin, the side walls of the overflow forming the inner walls of the inlets, the upper wall of the overflow forming the bottom wall of the mixing chamber, and the slab, adjacent the mixing chamber forming the upper wall of said chamber, all of the walls being of substantially uniform thickness.

2. In a one-piece china lavatory, the combination of a basin; a slab; and an extension formed at the rear of the basin below the slab, said extension having formed therein an overflow opening which at its upper end opens through the rear wall of the basin; and a water passage likewise formed in said extension, said water passage extending over the upper portion of the overflow and opening into the basin, and likewise extending downwardly along the upper portion of the sides of the overflow, and being provided with laterally-extending openings affording connections for supply pipes, the walls of the various passages being of substantially the same thickness throughout.

3. In a one-piece china lavatory, the combination of a basin; and an extension formed at the rear of the basin, said extension containing an overflow passage opening at its upper end through the wall of the basin and terminating at the lower end in the basin waste, and an inlet chamber for the water extending over the upper portion of the overflow and opening into the basin above said overflow, the inner wall of said water chamber forming the upper wall of the overflow passage, and said water chamber being provided with downwardly extending passages, the inner walls whereof are common with the side walls of the overflow passage, said passages each having a lateral

opening for connection of the supply fittings thereto, the walls of the various parts being of substantially the same thickness throughout.

4. In a one-piece china lavatory, the combination of a slab; of a basin and an extension formed on the rear wall thereof, said extension having formed therein an overflow passage terminating at its upper end in an opening in the rear wall of the basin, the lower end terminating in the basin waste, and said extension likewise having formed thereon an inverted substantially U-shaped water supply mixing chamber, between the top of the overflow and the under side of the slab and embracing the upper portion of the overflow extension and having an opening extending from the upper part into the basin and above the overflow opening; a laterally extending opening being formed in each of the lower ends of said mixing chamber for the connection of supply pipes thereto, the walls of the various passages and the chamber being formed of substantially uniform thickness.

5. In a one-piece china lavatory, the combination of a basin; a slab; and an extension formed on the exterior of the rear wall of the basin below the slab; said extension containing an overflow passage opening into the basin, and a water supply mixing chamber overlying and embracing the upper end and the upper side portions of the overflow passage, and integrally formed with same and the overlying slab, and likewise opening into the basin above the overflow opening, the slab and the walls surrounding said passage and chamber being formed of substantially uniform thickness, together with water supply connecting means, as and for the purpose set forth.

6. In a one-piece china lavatory, the combination of a slab; a basin with an extension formed upon the outer rear wall thereof below and extending downwardly from the slab, a vertically disposed opening through the slab on either side of the extension, an overflow passage formed within the extension and a mixing chamber between the slab and the extension formed integrally with the slab and the extension and embracing the top and upper side portions of the extension, all walls surrounding the various passages being of substantially uniform thickness; a lateral opening on either lower end of the mixing chamber in alignment with the vertical openings through the slab; a supply pipe connected to and extending laterally from each opening, and a valve connected to each pipe and lying, respectively, below the aforesaid openings in the slab, the heads of the valves extending upwardly through said openings.

7. A basin having a projection formed integrally therewith, said projection having an overflow passage.

- the upper portion of the basin and a water supply passage likewise formed in said projection, with portions of the walls of said passages in common, said portions having water jet openings extending therethrough and serving, when water is drawn through the supply passage, to project jets against the upper inner surface of said overflow passage.
- 10 8. In a one-piece china lavatory, the combination of a basin and a projection formed upon the outer face thereof, said projection having formed therein an overflow pas-

sage opening at its upper end into the basin, and an inverted U-shaped water supply passage, said water passage overlying the upper portion of the overflow passage, and said passages having a portion at least of their walls in common, with jet openings extending through such portion of the wall and serving, when water is drawn into the basin, to project water against the inner upper surface of the overflow passage. 15 20

In testimony whereof I have signed my name to this specification.

WINFIELD E. HINSDALE.
